DESIGN FOR A VASE.

Specification forming part of Design No. 7,511, dated June 30, 1874; application filed May 1, 1874.
[Term of Patent 7 years.]

CASE B.

To all whom it may concern:

Be it known that we, WILLIAM TWEEDDALE and JONATHAN MOORE, of Brooklyn, in the county of Kings and State of New York, have invented a new and original Design for a Vase, of which the following is a specification.

The nature of our design for a vase is fully represented in the accompanying photographic illustration to which reference is made.

The design consists, first, of the ornamental configuration of the border A; second, of the side ornaments B; third, of the bottom ornaments C; fourth, of the stand ornaments D; and, fifth, of the handle ornaments E; all as shown in the photographic illustration.

We propose to use the design of the border for aquariums also.

We claim as our invention—

1. The design for the border of the bowl of

a vase or aquarium, substantially as set forth, and represented at A.

2. The design for the bowl of a vase consisting of the side ornamental figures B, substantially as specified.

3. The design for the bottom of a vase consisting of the ornamental figures C.

4. The design for the standard of a vase, substantially as set forth, and represented at D.

5. The design for a vase consisting of the ornamental handles E, as shown and set forth.

6. The design for a vase consisting of the ornamental border A, side figures B, bottom figures C, standard D, and ornamental handles E, substantially as shown and set forth.

WILLIAM TWEEDDALE.
JONATHAN MOORE.
